UNITED STATES PATENT OFFICE.

JAMES T. SMITH, OF NEW YORK, N. Y.

UMBRELLA.

SPECIFICATION forming part of Letters Patent No. 398,666, dated February 26, 1889.

Application filed August 25, 1888. Serial No. 283,776. (No model.)

To all whom it may concern:

Be it known that I, JAMES T. SMITH, a citizen of the United States, residing at New York, in the county of New York and State of New York, have invented certain new and useful Improvements in Parasols, Umbrellas, and Canes; and I do hereby declare the following to be a full, clear, and exact description of the invention, such as will enable others skilled in the art to which it appertains to make and use the same.

My invention relates to an improvement in umbrellas, parasols, and canes.

The object of my invention is to provide a substitute for the well-known runner on a parasol or umbrella stick, used to slide upon the stick to cover and hold a joint in the same, and whereby, when it is not desired to fold the parasol or umbrella stick or to use the same as a cane, the runner and the joint are concealed from view. To this end the invention consists of the construction herein-after described and claimed.

The invention is illustrated in the accompanying drawings, in which—

Figure 1 is a longitudinal view in section; Figs. 2, 3, 4, and 5, details; and Fig. 6, a modification.

Referring to the drawings, A A' constitute portions of a rod connected by a joint, B. The portion A is secured solidly in any suitable manner to or within the longer upper part of a wooden or metal stick, C. The portion A' is placed within a tube, D, and is provided at its lower end with a pin, b', adapted to slide within a slot, b², of said tube. Near the end of the slot b² is a smaller slot, b³, at right angles to the former, and the two, with the sliding pin, form what is known as a "bayonet-joint."

The tube D is placed within a hollow shank or handle, F, which may be made of wood or metal. In order to secure the tube D within the handle F, the hollow in the handle may be made of about the same diameter as the tube, so as to permit the tube to be driven into the handle, and thus be held therein without further attachment; or the end of the tube may be provided with a screw-threaded shank, g, as shown, to engage with a screw-threaded recess, g', in the end of the handle F.

The handle can be of any length desired, and the mechanism thus described enables the length of the stick to be shortened by folding at about the center, when the jointed rod 55 is withdrawn from the handle, so that the joint will be beyond the handle. It deducts nothing from the appearance of an umbrella or parasol when the same is used, as the mechanism to produce the result is entirely concealed by the handle and the handle itself is not disfigured.

The invention is alike applicable to hollow and solid sticks, shanks, and handles, and to umbrellas and shades for baby-carriages and 65 other vehicles, as well as to those carried by hand, and also to canes for folding them when not in use.

Instead of the bayonet-joint in the tube, the slot may be spiral, or of any other desired 70 angle.

In Fig. 6 a modification is shown. G is a top stick, upon which the frame of a parasol may be attached, and is provided with a stop-ring, H, a jointed bit, I, and a short male-screw tube, K. L is the handle part, made hollow and having screwed at the open end thereof onto an internal thread a female-screw ferrule, M. The top stick, G, is inserted in the handle and passed down until the screw-tube K meets the ferrule M, when they are screwed together. When it is desired to withdraw the upper stick and bend or fold it, the handle is unscrewed and the stick part G is drawn until the joint I is out of the handle 80 and the stop-ring H comes in contact with the ferrule M, which prevents the entire withdrawal of the stick.

What I claim is—

1. In combination with a hollow handle of 90 an umbrella, parasol, or cane, a folding stick composed of the parts A A', connected by a joint or bit and adapted to slide into the handle, so as to conceal from view the said joint, and a lock within the handle to connect the 95 handle and stick, which lock is also concealed from view when the stick is in place within the handle, substantially as described.

2. In combination with the stick of an umbrella, parasol, or cane, a handle, a jointed rod 100 connecting the stick and handle, and a tube within and concealed by the handle, into

which the jointed rod is adapted to slide, substantially as described.

3. The combination of the stick, jointed rod, provided with a pin, the tube within which said rod is adapted to slide, and provided with a slot to receive said pin, and the hollow handle within which is secured said tube, substantially as described.

In testimony whereof I affix my signature in presence of witnesses.

JAS. T. SMITH.
